UNITED STATES PATENT OFFICE.

GEORGE W. PIERCE, OF CAMBRIDGE, MASSACHUSETTS.

APPARATUS FOR AMPLIFYING OR DETECTING ELECTRICAL VARIATIONS.

1,087,180.

Specification of Letters Patent. Patented Feb. 17, 1914.

Application filed November 26, 1913. Serial No. 803,358.

To all whom it may concern:

Be it known that I, GEORGE W. PIERCE, a citizen of the United States, residing at Cambridge, in the county of Middlesex and State of Massachusetts, have invented certain new and useful Improvements in Apparatus for Amplifying or Detecting Electrical Variations; and I do hereby declare the following to be a full, clear, and exact description of the invention, such as will enable others skilled in the art to which it appertains to make and use the same.

The present invention relates to apparatus for amplifying or detecting electrical variations.

The apparatus comprises a gaseous conducting medium upon which the electrical variations are impressed in such a manner as to modify the current in a local circuit through the gas.

The object of the invention is to make an improved apparatus of this type which is sensitive, reliable and rapidly responsive to the variations to be amplified.

The apparatus is particularly applicable to the amplification or detection of the electric signal variations or impulses of wireless telegraphy, wireless telephony, or telephony and telegraphy over wires and cables.

The present invention is preferably embodied in an apparatus comprising a mercury vapor device in which an evacuated space or region is ionized and rendered conducting by means of a mercury arc. The electrical variations to be amplified or detected are impressed by means of a controlling circuit upon a region in the ionized conducting gas or vapor and vary its apparent conductivity. A local or controlled circuit has a current path through the conducting gas or vapor. The change in the apparent conductivity of the gas causes variations in the current in the controlled circuit. These variations in the controlled circuit may be detected by some translating device in the controlled circuit or connected indirectly therewith.

In the drawings which illustrate the preferred embodiment of the present invention, Figure 1 is a diagrammatic view of the mercury vapor device connected with a telephone line; Fig. 2 shows the mercury vapor device connected with a telegraph line; Fig. 3 is a plan view of the shield; and Fig. 4 is a plan view of the grid-like electrode.

The mercury vapor device *per se* will first

be described and then the electrical connections and mode of operation will be described and pointed out.

The mercury vapor device comprises an evacuated glass bulb or tube 1. Supported on a leading-in wire which is sealed through the top of the tube is an electrode 2 which consists of a flat circular plate or disk of platinum or iron. A short distance below the electrode 2 is another electrode 3 which consists of a piece of platinum or iron wire bent back and forth to form a grid, as shown in Fig. 4, and connected with a leading-in wire sealed through the side of the tube. The electrode 3 may have the form of a grid, as illustrated, or may be made of a foraminous plate or of wire fabric or other open work structure. Sealed through the bottom of the tube is a platinum wire 4 which projects some distance into the tube. Above the platinum wire supported by a leading-in wire sealed through the side of the tube is an electrode 5 which consists of a flat circular plate or disk of iron with a hole 8 through it. This hole 8 is situated directly above the point of the platinum wire 4. The tube contains a body of liquid mercury 6, the level of which is such that the point of the platinum projects slightly from the surface of the mercury. An extension 7 is blown into the side of the tube near the bottom into which the surplus mercury may be spilled to adjust the mercury level with respect to the platinum wire. The circular perforated plate 5 and the body of mercury 6 form the electrodes or terminals for a mercury arc which is maintained by means of a "keep alive" circuit 10 which includes the battery 11 and ballast resistance 12 and inductance 13. The platinum wire 4 acts to keep the arc from skipping around over the surface of the mercury and holds it at the point of the platinum wire. The action of the mercury arc in conjunction with the controlled circuit 30 hereinafter described is believed to cause a stream of negative ions or electrons to arrive at the surface of the electrode 2 by flowing chiefly through the hole 8 in the plate 5. The plate intercepts the electrons around the hole 8 and so shields the upper part of the tube from the electrons discharged from the arc with the exception of the stream flowing through the hole 8 or a comparatively unimportant indirect flow around the edge of the plate 5. Since the arc is centered below the hole 8, a concentrated and directed stream

of electrons is directed through the hole 8 and upon the electrode 2 at the top of the tube. The plate 5 besides being a positive electrode or anode has, as above pointed out, 5 the function of substantially shielding the upper part of the tube from the electrons given off by the arc except for the directed stream through the hole 8, and, therefore, may be referred to for convenience as the 10 "shield".

While the dimensions of the mercury vapor device may be varied, it is found that a mercury vapor device having substantially the following dimensions operates successfully: The distance from the surface of the mercury to the shield 5 is about one-half inch. The distance from the shield 5 to the open work electrode or grid 3 is about five inches. The distance from the electrode 3 to the electrode 2 is about one and one-quarter inches. The shield 5 is about one inch in diameter and has a hole of about a quarter of an inch diameter through its center. The electrode or grid 3 has substantially a square outline of about one and one-eighth inches across. The electrode 2 is a little less than an inch in diameter. The pointed tip of the platinum wire 4, the hole 8, the electrode or grid 3 and the electrode 2 are all in line so that the stream of electrons shot off from the mercury arc are directed through the center of the grid 3 against the middle of the electrode 2.

As far as the construction of the tube 35 itself and the "keep alive" circuit for the mercury arc are concerned, the modifications illustrated in Figs. 1 and 2 of the drawings are identical.

In the apparatus illustrated in Fig. 1, 20 40 indicates a telephone line or circuit in which is included the primary 21 of a transformer 22, preferably a step-up transformer. One end of the secondary 23 of the transformer is connected by means of a receptor lead 25 45 to the electrode 3 and the other end of the secondary is connected by means of a receptor lead 26 to the electrode 2. The leads 25 and 26 and their connections with the telephone circuit constitute what may be termed 50 the "controlling" circuit 28 by means of which the electrical potential variations set up in the transformer 22 are impressed upon the sensitive ionized mercury vapor in the tube. The electrode 2 is connected with one 55 of the arc terminals, preferably the anode plate or shield 5, by means of the electric circuit 30 including a battery 31 and the primary 32 of the transformer 33. The circuit 30 since its current is varied or controlled by means of the mercury vapor device 60 may for convenience be referred to as the "controlled" circuit. The negative pole of the battery 31 is connected to the electrode 2. The battery 31 has an electro-motive force of about one-half volt to five volts.

The secondary 34 of the transformer 33 is connected to a telephone receiver 35 which constitutes the translating means by means of which the signals are detected. Instead of the telephone receiver 35, the transformer 70 may be connected with a telephone line and the amplified telephonic waves relayed to a distant station. The battery 31 causes but a very small current flow through the circuit 30. This is probably due to the fact 75 that the directed stream of electrons shot off from the mercury arc and impinging upon the electrodes 2 and 3 is what may be termed a convection current of negative electricity and thus acts in opposition to the battery and pretty effectually prevents the battery from forcing any considerable current 80 through the tube. When a telephone message is transmitted over the telephone line, corresponding variations in electro-motive force are impressed by means of the controlling circuit 28 upon the electrodes 2 and 3. These impressed variations cause corresponding changes or variations in the apparent conductivity of the sensitive gas in 85 the tube and thereby cause corresponding variations to take place in the current in the circuit 30. The current variations in the circuit 30 are usually of much greater energy than the variations in the telephone line. 90 Thus the telephonic waves received over the telephone line 20 are amplified and may be heard in the receiver 35 or relayed to a distant station. 95

In Fig. 2 is illustrated an apparatus particularly adapted for use in connection with telegraph lines. The positive and negative wires 40 and 41 of the telegraph line are connected with the electrodes 3 and 2 respectively, and constitute the controlling circuit 100 105 28 by means of which the variations of electro-motive force are impressed upon the mercury vapor device. The controlled circuit 30 is connected between the electrode 2 and the mercury arc and includes the battery 31, and the relay 42. The negative pole of the battery 31 is connected to the electrode 2. The battery has an electro-motive force of from about one-half volt to five volts. The relay 42 operates upon an increase of current in the circuit 30 to close a local sounder 110 115 44. The relay 42 may, if desired, be used to control another telegraph line by means of which the relayed message may be transmitted to a distant station. When the telegraph key at the distant sending station is depressed, the wire 40 and electrode 3 have a positive potential with relation to the wire 41 and electrode 2, and this difference of potential force operates to increase the apparent conductivity of the tube and so increase the current in the controlled circuit 30. When the sending key is released at the end 120 125 of the dot or dash signal and the difference in potential of the wires 40 and 41 is no 130

longer maintained, the tube restores itself to a condition of decreased conductivity and the current in the circuit 30 is decreased. These variations in the controlled circuit 30 5 cause the relay 42 to operate and relay the dot and dash signals. The current increases in the controlled circuit 30 are usually variations of much greater energy than that of the signal impulses transmitted over the 10 wires 40 and 41. Consequently, the device may be employed to amplify very faint received telegraphic messages.

The apparatus of the present invention is also applicable to wireless telegraphy and 15 telephony. In use with wireless telegraphy or telephony, an arrangement similar to that illustrated in Fig. 1 is preferred, the principal difference being that the transformer 22 will be an oscillation transformer, and 20 the transformer primary 21 will be connected to the oscillation circuit of the wireless receiving system, as shown, for example, in my co-pending application Serial No. 803,357, filed of even date herewith. In this 25 case, the train of Hertzian waves which make up the wireless signals cause correspondingly rapid oscillations in the relative potential of the electrodes 2 and 3, and this causes an increase in the current through 30 the controlled circuit 30, as long as the train of Hertzian waves lasts. In the case of wireless telegraphy, the dots and dashes, each made up of a train or trains of Hertzian waves, will cause corresponding in- 35 creases in the current in the controlled circuit 30 and the signals will be heard as dots and dashes in the telephone receiver 35. In the case of wireless telephony, the telephonic waves consist in variations of telephonic frequency in the intensity of trains of waves of 40 Hertzian frequency. When a wireless telephone message is being received, the more intense the received train of waves is, the greater are the potential oscillations of 45 Hertzian frequency between the electrodes 2 and 3, and the greater is the battery current in the controlled circuit 30. The variations of telephonic frequency of intensity in the train of Hertzian waves, therefore, cause 50 corresponding variations in the current flow in the circuit 30, and consequently the telephonic waves are audible in the receiver 35.

While the operation of the device is not perfectly understood, it is believed that 55 there is a rectifying action at the open work electrode 3, and that a discharge of electricity can take place in only one direction from the electrode 3. The mercury vapor device *per se* is described and claimed in my 60 co-pending application Serial No. 803,357, filed of even date herewith. One of the essential differences between the apparatus described in this application and that in my co-pending application is the arrangement 65 of the battery 31 which, in the apparatus of

this application, has its negative pole connected to the electrode 2 and operates to send an increased amount of current through the tube 1 when the electrode 3 is made positive or oscillations are impressed upon it, whereas in the apparatus described in my co-pending application Serial No. 803,357, the positive pole of the battery 31 is connected to the electrode 2 and operates to send a decreased amount of current through the tube 1 when the electrode 3 is given a negative charge or when oscillations are impressed upon it. In the drawings of my co-pending application Serial No. 803,357, are indicated a number of ways in which the amplifying apparatus of the present application might be connected with wireless systems, with this difference, however, namely, that whereas in the connections shown in said co-pending application a condenser is interposed in one of the receptor leads 25 and 26 between the oscillation transformer and the mercury vapor tube, no such condenser would be used in the receptor leads 25 and 26 between the oscillation transformer and the mercury vapor tube in applying the present apparatus to wireless work. The region between the electrodes to which the controlling circuit is connected has impressed upon it static variations of electro-motive force and these static variations are apparently accompanied by more or less of a transfer of electricity between said electrodes. It will be noted that the region in the tube subject to the action of the controlling circuit is not co-extensive with the region which forms the current path of the controlled circuit and that these regions have a part only in common.

The expression "controlling circuit," as used in the specification and claims is intended to define an electric circuit by means of which the electrical variations to be amplified are impressed upon the sensitive conducting gaseous medium, and the expression "controlled circuit" is intended to define the electric circuit which is controlled thereby.

The present invention is not limited to its illustrated embodiment, but may be embodied in other constructions within the scope of the following claims.

I claim—

1. An apparatus for amplifying or detecting electrical variations having, in combination, an evacuated vessel, an ionizing means therein, two electrodes in the vessel exposed to the ionizing means, a controlling electric circuit connected with the two electrodes, and a controlled electric circuit including a uni-directional source of electro-motive force having its positive pole connected to the ionizing means and its negative pole connected with one of the electrodes.

2. An apparatus for amplifying or detecting electrical variations having, in combination, an evacuated vessel, an ionizing means therein, an electrode in the vessel, a second electrode in the vessel between the ionizing means and the first electrode, a controlling electric circuit connected with the two electrodes, and a controlled electric circuit including a uni-directional source of electro-motive force having its positive pole connected with the ionizing means and its negative pole connected with the first electrode.
3. An apparatus for amplifying or detecting electrical variations having, in combination, an evacuated vessel, ionizing means in the vessel, an electrode in the vessel, a second open work electrode between the ionizing means and the first electrode, a controlling circuit connected with the open work electrode, and a controlled circuit including a uni-directional source of electro-motive force having a positive pole connected with the ionizing means and its negative pole connected with the first electrode.
4. An apparatus for amplifying or detecting electrical variations having, in combination, an evacuated vessel, an ionizing means for maintaining a body of sensitive conducting gas therein, means for impressing static electrical variations upon a region in the conducting gas, and a controlled circuit having through the conducting gas a current path which has a part only in common with said region and including a uni-directional source of electro-motive force having its positive pole connected with the ionizing means and its negative pole connected with the electrode.
5. An apparatus for amplifying or detecting electrical variations having, in combination, an evacuated vessel, ionizing means in the vessel, an electrode in the vessel, a controlled electric circuit including a uni-directional source of electro-motive force having its positive pole connected with the ionizing means and its negative pole connected with the electrode, and means for increasing the

apparent conductivity of the current path of the controlled circuit through the vessel comprising a second electrode and a controlling circuit connected with the first and second electrodes for impressing variations of the electro-motive force upon said two electrodes.

6. An apparatus for amplifying or detecting electrical variations having, in combination, an evacuated vessel, means for maintaining a mercury arc therein, two electrodes, a controlling electric circuit connected with the two electrodes, and a controlled circuit including a uni-directional source of electro-motive force having its positive pole connected with the mercury arc and its negative pole connected with one of the electrodes.

7. An apparatus for amplifying or detecting electrical variations having, in combination, an evacuated vessel, ionizing means in the vessel, an electrode exposed to the ionizing means, a controlled electric circuit including a uni-directional source of electro-motive force tending to cause a current to flow between the electrode and ionizing means in opposition to the ionizing means, and means for varying the apparent conductivity of the ionized region within the vessel including a second electrode in the vessel.

8. An apparatus for amplifying or detecting electrical variations having, in combination, an evacuated vessel, a mercury arc for maintaining a body of sensitive conducting mercury vapor therein, means for impressing static electrical variations upon a region in the conducting vapor, and a controlled circuit having through the conducting vapor a current path which has a part only in common with said region and including a uni-directional source of electro-motive force having its positive pole connected with the ionizing means and its negative pole connected with the electrode.
